Primary Examiner—T. Chase Nelson*Assistant Examiner*—Barbara Blanton Lohr(74) *Attorney, Agent, or Firm*—John G. Fischer; Storm LLP(57) **CLAIM**

The ornamental design for butterfly frames, as shown and described.

DESCRIPTION

FIG. 1 is an isometric view of the butterfly frames of my design;

FIG. 2 is an enlarged, partial, front view of the butterfly frames, showing the right side of the design thereof;

FIG. 3 is an enlarged, partial, rear view of the butterfly frames, showing the left side of the design thereof;

FIG. 4 is an enlarged, partial, top view of the butterfly frames, showing the right side of the design thereof;

FIG. 5 is an enlarged, partial, bottom view of the butterfly frames, showing the right side of the design thereof;

FIG. 6 is an enlarged, partial, side view of the butterfly frames, showing the outer right side of the design thereof; and,

FIG. 7 is an enlarged, partial, side view of the butterfly frames, showing the inner left side of the design thereof.

In all views in which only one side of the butterfly frames is depicted, the opposite side is a mirror image.

The dashed lines presented in the drawings are for illustration purposes only, and do not form part of the claimed design.
